CLAIM

The ornamental design of a training bat, as shown and described.

DESCRIPTION

The patent or application file contains at least one drawing executed in color. Copies of this patent or patent application publication with color drawings will be provided by the Office upon request and payment of the necessary fee.

FIG. 1 is a perspective view of the training bat of my design; FIG. 2 is a front elevational view of the training bat of FIG. 1;

FIG. 3 is a rear elevational view of the training bat of FIG. 1;

FIG. 4 is a top plan view of the training bat of FIG. 1; FIG. 5 is a bottom plan view of the training bat of FIG. 1; FIG. 6 is a left end elevational view of the training bat of FIG. 1;

FIG. 7 is a right end elevational view of the training bat of FIG. 1; and,

FIG. 8 is an enlarged view of the handle portions of the training bat taken from the breakout circle 8 of FIG. 2. The bat grip of the training bat shown in FIGS. 1 to 8 is shaded for the color red.

1 Claim, 5 Drawing Sheets
